DUSTING MACHINE

Miles H. Tuft, Huntington Park, Calif., assignor
to Hardie Manufacturing Company, Hudson,
Mich., a corporation of Michigan

Application February 5, 1951, Serial No. 209,384

4 Claims. (Cl. 43—148)

1

This invention relates to machines for spreading finely comminuted material such as insecticide dust, and more particularly relates to machines for dusting ground crops with air-borne powders. Because an obviously desirable quality in such machines is ability to cover a wide strip or area in each traverse of a field, and because the density or concentration of the dust cloud at a point distant from the point of initial dust-air mixture depends to a large extent upon a smooth velocity gradient between the two points, such machines present problems in coordination of size of the machine and velocity control of the finely comminuted material which it is a general object of this invention to solve.

More specifically, it is an object of this invention to provide a dusting machine capable of dusting a strip of ground extending widely on both sides of the track of the vehicle transporting the machine, and capable of being compacted to a size suitable for road travel, and yet capable of delivering evenly spaced jets on air-borne dust of even concentration across the full width of the machine's traverse. In the attainment of this object, I utilize hollow booms as ducts for the air-dust mixture, these booms being foldable to suitable road positions and being of tapered construction so as to provide substantially constant velocity for the diminishing volume of the mixture in a manner not practical with flexible extension hoses.

Another object of my invention is to provide a dusting machine of very considerable width which has rigid tubular ducts in which the air-dust jets are normally close to the ground to obtain the value of high velocity impingement of the dust upon the traversed foliage, yet having the ducts mounted to yield to obstructions and to swing automatically back to their operating positions when the obstruction has been passed.

Still a further object of the invention is to provide a dusting machine in which the aforementioned ducts are fed an air-dust mixture in substantially even volume from a central section housing a centrifugal fan which also supplies the area between the ducts with a proportionate volume of the mixture so that even distribution is attained for the full width of the machine.

Further objects and useful advantages of my invention will be pointed out as the following description of a preferred embodiment of my invention proceeds, or will be apparent from the description considered in connection with the accompanying drawings illustrative of that embodiment, in which:

2

Fig. 1 is a rear elevational view of my improved dusting machine, it being understood that the left-hand boom, shown broken away, is symmetrical with the right-hand boom, and that the machine will normally be mounted upon a tractor or other vehicle providing a source of power, not shown;

Fig. 2 is a bottom plan view, in which both booms are broken away, illustrating the system of jet openings in the under surfaces of the machine;

Fig. 3 is a side elevational view on a slightly enlarged scale, taken from the left of Fig. 1;

Fig. 4 is a top plan view, on a reduced scale, showing the booms in extended position and, in broken line, in their folded or road-traveling position;

Fig. 5 is a detailed rear elevational and fragmentary view, on further enlarged scale, of the hinge attachment of a left-hand boom, the boom being shown also in its folded position in broken lines;

Fig. 6 is a sectional view on the plane of section 6—6 of Fig. 5, showing further details of the hinge attachment of the boom, and of gasket sealing means for the hinged joint; and

Fig. 7 is a vertical sectional view on the plane of section 7—7 of Fig. 2, and on an enlarged scale illustrating a preferred arrangement of baffles within the central fan housing, the fan itself being shown in elevation.

Having reference now to the details of the drawings, my improved dusting machine has as its principal components a central casing 10 housing a centrifugal fan 11 to which dust is supplied from a hopper 12, and tubular booms 14 hinged to opposite ends of the casing 10 and normally aligned in the plane in which the fan 11 rotates. The entire structure will normally be supported by suitable framework 15 upon a tractor or other vehicle, not shown, having a power take-off for operating the fan 11. The hopper 12 and the feed mechanism therefrom to the centrifugal fan 11 may be of any type which will provide a substantially constant flow of dust, a suitable type having a convenient method of regulating the dust flow being shown in my co-pending application Serial Number 133,331, filed December 16, 1949. The central casing 10 with its attached booms 14 will be mounted transversely of the tractor, with the hopper 12 mounted forwardly and connected to the casing 10 adjacent the shaft of the fan 11 by a conduit 16. The power take-off of the tractor will be connected to a wheel 17, from which a belt 18 drives a wheel 19 mounted 55 on the fan shaft.

Each of the booms 14 is attached to the casing 10 by a bracket 20 constructed and hinged to permit both rearward and upward motion and consequently a rearwardly and upwardly swing compounded of these motions. The brackets 20 are hinged to the casing 10 by vertical hinge posts 21 secured to their rearward margins, the posts 21 turning in lugs 22 on the rearward face of the casing 10. The brackets 20 arch over the upper sides of their respective booms 14 and pivotally support horizontal trunnions 24 on the forward and rearward sides of the booms. The posts 21 and trunnions 24 form universal joints permitting the aforesaid compound swing in three dimensions. The booms 14, of course, are hollow to serve as ducts for the air-dust mixture and at their open inward ends they mate with openings 25 in the ends of the casing 10. To seal the hollow booms against the perimeters of the openings 25, the booms are provided with large soft gaskets 26, preferably of sponge rubber or material of like resiliency, set in collars 26a which may be secured to the booms by suitable reinforcing members 26b, the latter also securing the trunnions 24 to the booms.

Movement of the booms 14 is limited and controlled by swinging supports 27. These supports may be cables or rods but more conveniently are chains which may be easily adjusted for length. The end plates 28 of the casing 10, in which the openings 25 occur, are extended upwardly and braced to the central casing 10 by braces 29. The chain supports 27 are secured by bolts 30 to the upper forward corners of the frames 28—that is, to positions on the frames 28 well above the trunnions 24 and well forwardly of the hinge posts 21 upon which the booms pivot rearwardly—and they are secured to the booms 14 by bolts 31 well outwardly from the brackets 20 and are adjusted in length to permit the booms to extend horizontally and to seat firmly against the openings 25, when the booms are in normal laterally extended operating positions. To permit the chains 27 to swing rearwardly without obstruction, the plates 28 are cut away as shown at 32.

It will be seen that when the booms 14 swing rearwardly about the posts 21, they will also be constrained by the chains 27 to pivot upwardly about the trunnions 24, and that the booms will attain their highest elevation when they are pointed rearwardly and the chains 27 pass directly over the posts 21. After passing these high positions the booms will respond to gravity to swing to lower and convergent positions as shown in broken lines in Fig. 4.

Because the booms 14 may thus be folded rearwardly, the casing 10 may extend entirely across the transporting vehicle and still be suitable for highway travel. Thus space is provided for a large powerful fan and large dust mixing chambers, all in the vertical transverse plane in which the booms operate. The fan shaft 34 extends through an opening 35 in the forward side of the casing 10, and through an opening 36 in the rearward side of the casing, where it may be supported on a hanger 37. The openings 35 and 36 admit carrier air to the fan 11, and the opening 35 also admits the conduit 16 leading from the hopper 12. A guard 38, shown partly broken away in Fig. 1, protects the pulleys 17 and 19 and the belt 18 and also serves as a stop or bumper against which the booms 14 may rest when they are folded.

As shown in Fig. 2, the under surface of the casing 10 has openings 40 and the under surfaces

of the booms 14 have openings 41 for the emission of air-borne dust. To obtain mixture and distribution the casing 10 has a number of interior baffles, shown in Fig. 7, and may be disposed asymmetrically with respect to the fan 11. Fig. 7 shows the fan 11 arranged to rotate in a clockwise direction and it will be noted that the end of the casing 10 towards which the fan blades sweep upwardly is considerably shorter than the opposite end. In the shorter mixing chamber 42, I prefer to provide a plurality of baffles 43 arranged to deflect the air-dust mixture downwardly toward the openings 40 and outwardly toward the adjacent opening 25, and to incline the upper plate of the casing 10, as shown at 44, so that that portion of the casing also serves as a directing surface. In the opposite longer mixing chamber 45 a single downwardly deflecting baffle 46 and the inclined upper plate 47 will suffice to direct the air-dust mixture to the openings 40 and the adjacent opening 25. The power shaft 48 to the driving pulley 17 is protected by an inner casing 49, from which a short baffle 50 extends towards the chamber 42. A line drawn from the uppermost baffle 43 to the baffle 50 substantially bisects the fan 11; dust quantity departing from the fan to the left of such a line and to the right thereof will be substantially equal.

To maintain the dust in suspension within the casing 10 and booms 14, the velocity of the carrier air must be maintained, despite the loss of air through the emission openings 40 and 41 as the air proceeds towards the ends of the booms. The inclined casing plates 44 and 47 diminish the cross-sectional area of the casing 10 toward each of the openings 25, and the booms 14 are tapered from the openings 25 toward their outer ends so that the air-dust mixture, though losing volume through the emission openings, has substantially constant velocity and the pressure at all of the emission openings is substantially equal.

As heretofore stated, the booms 14 will normally be folded in crossed position during road-travel, being then held by gravity in contact with each other or with the guard 38 or other stop provided for the purpose. The weight of the booms will prevent their swaying or jostling. When extended to operating position, their weight again holds them in extended position and seals the gaskets 26 against the rims of the openings 25. If one of the booms encounters an obstacle, such as a tree or a wall, it is free to swing rearwardly and at the same time will swing upwardly so as to clear any low obstruction and return quickly to its operating position. It may not be forced rearwardly to its highest elevation—from which it might swing to its folded position—by any obstacle which the casing 10 would clear. When a boom is momentarily moved rearwardly, some dust will be lost at the unsealed opening 25, but by the use of thick sponge gaskets 26 the loss can be minimized when the swing of the boom is only a few degrees; and if the swing is wide, the dust will be blown in the plane normally occupied by the boom and generally downward because of the inclined plates 44 and 47.

I wish it understood that modifications of the embodiment herein described, within the scope of the appended claims, are to be considered as included within the spirit and scope of the invention.

I claim:

1. In a dusting machine, a centrifugal fan; a source of dust supply arranged to feed dust

to said fan; a casing for said fan elongated in the plane of rotation of said fan and having horizontally directed end openings at levels below the axis of said fan; hollow booms respective to said openings having open ends adapted to seal against said openings to receive dust therefrom, and having downwardly directed orifices for the emission of dust; means pivotally supporting said booms whereby said booms may be moved out of sealing engagement with said end openings; and baffles within said casing inclined downwardly adjacent to said end openings, whereby dust emitted from said end openings when said booms are moved therefrom is directed downwardly in like manner to dust emitted from said orifices.

2. In a dusting machine, a casing having an outlet for dust; a hollow boom, having outlets for dust and having an open end mating with said casing outlet to provide a continuous passage from said casing to said boom outlets; pivot means supporting said boom on said casing for movement in inclined planes, whereby said boom may swing upwardly and laterally upon encounter with an obstacle and may return to its original position by gravity; and gasket means for sealing said open end of said boom to said casing outlet under gravitational pressure of said boom.

3. In a dusting machine, apparatus as set forth in claim 2, in which said gasket means is of such thickness and resiliency as to continue to seal during small oscillations of said boom.

4. In a dusting machine, a casing having an

outlet for dust; a hollow boom, having outlets for dust and having an open end mating with said casing outlet to provide a continuous passage from said casing to said boom outlets; hinge means supporting said boom on said casing for movement in a horizontal plane; additional hinge means supporting said boom on said casing for movement in a vertical plane; means of fixed radius connecting an outward portion of said boom to a portion on said machine above said hinge means for causing said boom to swing concurrently upon both of said hinge means in an upwardly inclined arc; and a thick resilient gasket for sealing said open end of said boom to said casing outlet under gravitational leverage of said boom when said boom is at the lower end of said arc.
